UNCOUPLING DEVICE

Ole K. Kjolseth, Erie, Pa., assignor to General
Electric Company, a corporation of New York

Application September 26, 1939, Serial No. 296,585

5 Claims. (Cl. 213—163)

My invention relates to uncoupling devices and more particularly to uncoupling devices adapted for use with retractable railway vehicle couplers.

It is an object of my invention to provide an improved operating mechanism for an uncoupling device, especially an uncoupling device for use with retractable railway vehicle couplers.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawings in which Fig. 1 is an elevational view of portions of two locomotive units coupled together by means of a coupler embodying the principles of my invention; Fig. 2 is an enlarged sectional view of the coupler disclosed in Fig. 1 in the extended position; Fig. 3 is similar to Fig. 2 but illustrates the coupler in the retracted position; Fig. 4 is a sectional view illustrating the lock lifter and operating mechanism therefor in the unlocked position; Fig. 5 is a plan view, partly in section, of a coupler embodying the principles of my invention; Fig. 6 is an elevational view of the lock lifter disclosed in Figs. 2, 3 and 4; and Fig. 7 is another view of the lock lifter shown in Fig. 6.

In accordance with my invention I have provided an uncoupling device for uncoupling couplers 34 illustrated as joining two electric locomotive units 10, as shown in Figs. 1 and 2. In order to uncouple the couplers 34 I have provided a lock lifter 111 which is arranged to be pivoted about a pivot or fulcrum point 116 to operate a lock lifter 117. For this purpose I have provided an operating member or lever 112 pivotally and removably connected to the lock lifter 111, and a second member or lever 113 pivotally connected to the member 112. The member 113 is also pivotally connected to the railway vehicle and I have provided a third member or lever 114 which is pivotally connected to the member 113. The lever 114 is provided with an operating handle 115. Upon moving the handle 115 toward the front of the unit, as viewed in Fig. 2, it will be seen that the second member or lever 113 will be rotated about its pivotal mounting thereby causing member 112 to apply a force to lock lifter 111 thereby causing the lever to rotate in a clockwise direction about fulcrum 116, this movement resulting in forcing the knuckle thrower or lock releasing member 117

upwardly. The lock lifter 111 is so constructed that the member 112 may be disengaged therefrom when the coupler is in the retracted position as shown in Fig. 3.

Describing my invention in greater detail, an electric locomotive is shown comprising two similar units, each having a frame including a superstructure 10 which is supported by center bearings 11 on main truck frames 13 and 14. To facilitate traversing curves in the track, the outer ends 15 and 16 of the main truck frames 13 and 14, respectively, are supported by center bearings, not shown, on pivoted guiding trucks 19 and 20, respectively. These guiding trucks are of the double axle type provided with wheels 21 mounted on axles 22 journaled in journal boxes 23 which support the guiding truck frames.

The draft rigging on the forward end of each unit of the locomotive is of the retractable type in order to provide for the encasing of the draft rigging in front of the first unit to provide a smooth outer surface at the forward end of the locomotive. The arrangement of the draft rigging at the forward end of each unit is shown 20 in its extended position in Figs. 2, 4 and 5, and in its retracted position in Fig. 3. The draft rigging comprises a coupler 34 of the tight-lock type which is constructed to eliminate free slack between engaged couplers, and is provided with a 25 longitudinally extending shank 35 in which two openings 36 and 37 are formed. This coupler shank 35 extends within a coupler pocket formed between upper and lower plates 38 and 39, respectively, of the forward supporting frame end 30 35 of the main truck 13, and is supported on the lower plate 39 by a laterally slidably resilient member comprising a bearing guide block 40 which extends within an opening, not shown, formed in the lower side of the shank 35. The bearing block 40 is slidably mounted on the upper surface 46 of a laterally extending and longitudinally movable supporting track 47. The laterally extending track 47 is mounted on a pair of longitudinally extending tracks 48 formed on the lower plate 39 of the main truck frame. The longitudinally movable laterally extending track 47 is moved to its forward or extended position by a downwardly extending stop 49 secured to the underside of the rear wall of the bearing block 40 and is limited in its forward movement by stops 50 secured to the forward end of the longitudinally extending tracks 48. The laterally extending track 47 is retracted or moved inwardly on the longitudinally extending track 48 by a 50 projection 51 formed on the coupler 34, which en-

gages the edge of a top plate forming the upper surface 46 of the laterally extending track, as shown in Fig. 3.

The inner end of the coupler shank 35 is supported by a ball and socket joint including a socket 52, which is secured within the opening 37 in the shank 35 by welding or some similar manner, and a ball 53, which rotatably engages the inner surface of the socket 52. The ball 53 is provided with an axially and vertically extending cylindrical opening 54, and is pivotally secured to the end of the main truck supporting frame by a pivot pin 55 which extends through bearings 56 and 57 and openings formed in the upper and lower main truck plates 38 and 39, respectively. A retaining plate 68 is arranged in a groove 59 formed in the lower plate 39 adjacent the lower end of the bearing 57, and is provided with a tapered surface 61 adjacent the correspondingly tapered lower end of the pivot pin 55 for retaining and supporting the pivot pin in position. A groove 62 is formed in the upper end of the pivot pin 55 and a bifurcated latching bar 63 having fingers 64 is arranged to engage the groove 62 and a groove 65 formed in bosses 66 on the upper plate 38 adjacent the top of the bearing 56 and latches the pivot pin 55 in position in the end 15 of the main truck supporting frame. The latching bar 63 is biased into latched position by a compression spring 67 held under compression between a boss and spring seat 68 formed on the latching bar 63, and a spring seat plate 69 secured by bolts 70 to projections 71 formed on the upper plate 38 of the end 15 of the main truck supporting frame. A handle 72 is formed on the outer end of the latching bar 63 and is arranged to withdraw the fingers 64 from engagement with the grooves 62 and 65 to permit removal of the pivot pin 55. The latching bar 63 may be locked in the open position by the engagement between a notch 71a in bar 63 and plate 69. The pivot pin 55 is arranged to be disengaged from the ball bearing 53 and the supporting frame bearings 56 and 57 and is provided with a lifting loop 73 secured in the top of the pivot pin and engaged by a hook 74 formed on the lower end of a threaded rod 75. The rod 75 threadedly engages a hand-wheel, not shown, which is suitably rotatably mounted on the locomotive supporting frame, not shown.

In order to properly lubricate the ball and socket bearing, an opening 83 is formed through the pivot pin 55 and communicates with an annular groove 84 formed in the ball bearing 53. A set of radial grooves 85 communicates between the groove 84 and peripherally extending grooves 86 formed on the outer periphery of the ball 53. Lubricant is supplied through the opening 83 to the annular groove 84, and thereby lubricates the cylindrical bearing surface between the pivot pin 55 and the ball 53, and also passes through the radial grooves 85 to the peripherally extending grooves 86 and lubricates the bearing surface between the ball 53 and socket 52. In this manner, a universal force transmitting connection is formed between the coupler shank 35 through the ball and socket universal joint and the pivot pin 55 with the end of the main truck supporting frame, which provides for the transmission of forces between the coupler 34 and the main truck frame 13 without free slack between the force transmitting elements of the draft rigging.

In order to provide for positive actuation to extend and retract the draft rigging to a plurality of predetermined positions, a longitudi-

nally extending flange 87 is formed on the inner end of the coupler shank 35 and a gear rack 88 is pivotally secured by a pivot pin 89 to the flange 87 on the coupler shank. The gear rack extends 5 longitudinally through an opening 90 formed in a wall 91 extending between the upper plate 38 and lower plate 39 of the supporting frame end 15. The lower side of the gear rack 88 is supported by a roller 92 rotatably secured by a pin 93 to walls 94 extending between the upper and lower plates 38 and 39, respectively. A spur gear 95 engages the gear rack 88 and is secured to a shaft 96 and rotatably supported thereby on the walls 94 of the supporting frame. The shaft 96 extends laterally through a boss 97 formed on the side of the main truck supporting frame 15, and is provided with a set of reduction spur gears 98 and 99, mounted on the shaft 96 and an operating shaft 100, respectively. A square head is formed on the shaft 100 and is adapted to fit a socket wrench for rotating the shaft and the set of spur gears to move the gear rack 88 and the coupler longitudinally of the main truck supporting frame.

When the forward end of a unit of the locomotive is not coupled to another unit of the locomotive or to a railway vehicle, the draft rigging is adapted to be retracted within the housing or pocket formed between the upper and lower plates 38 and 39 of the end 15 of the main truck supporting frame. In order to retract the draft rigging, it is first necessary to disengage the pivot pin 55 from the ball 53. In order to do this, the latching bar 63 is pulled out by the handle 72, and the hand wheel, not shown, is rotated so as to lift the pivot pin 55 upwardly out of engagement with the bearings 56 and 57 in the openings formed in the main truck supporting frame and out of the cylindrical opening 54 through the ball 53. The spur gears are then rotated in such a direction as to draw the gear rack 88 in a backward direction, until the opening 36 in the coupler shank 35 is in alignment with the openings through the bearings 56 and 57 in the main truck supporting frame. In this position, the coupler 34 is entirely within the housing formed by the upper and lower supporting frame plates 38 and 39, respectively. The hand wheel is then rotated so as to lower the pivot pin 55 through the bearings 56 and 57 in the main truck supporting frame and through the opening 36 in the coupler shank 35. The latching bar 63 is then returned to its latched position and biased to this position by the spring 67. In this manner, the pivot pin 55 is arranged to secure the coupler in a plurality of predetermined positions on the main truck supporting frame and retains it thereon in either its extended or retracted position.

In order to provide a smooth, continuous outer surface at the front of the locomotive when the coupler is retracted, a closure plate 103 is secured by screws 104 at the top thereof to the upper plate 38 of the main truck frame. A flange 105 is secured, as by welding, to the lower edge of the closure plate 103. Member 105a, in turn, is secured to the front edge of the lower plate 39 of the main truck supporting frame, as by bolts 109a and to the plate 107 as by welding. Pins 109 are suitably secured to flange 105a and extend through suitable openings in flange 105. Thus, plate 103 is removed by unscrewing bolts 104 and lifting plate 103 until flange 105 is free of pins 109. A buffer 110, formed of a rubbery material, such as resilient

rubber, is secured by screws 110a to the outer end of the upper frame plate 38 above the closure plate 103.

In order to operate the knuckle lock for uncoupling the locomotive units 10, I have provided the following operating mechanism. The lock lifter 111 comprises a relatively stationary element including a lug or ear 118 suitably secured to a plate-like member 119 as by welding. The lock lifter 111 is pivotally connected to a coupler operating device such as the knuckle throwing member 117 as by means of a pin 120 inserted through suitable openings in member 117 and lug 118. In order to permit the lock lifter 111 to be pivoted about the fulcrum 116, I have provided a hook-like member 121 suitably secured to the plate 119 as by welding.

In order to provide for a pivotal connection between the lock lifter 111 and the member 112, I have provided a clasp 122 which is suitably hinged to a lug 123, the lug being suitably secured as by welding for example to the underside of the member 119. As illustrated I have provided for this purpose ears 124 integral with the clasp 122 and a pin 125 extending through suitable openings in lug 123 and ears 124. I have shown the pin 125 held in place by means of a washer 126 and the cotter-key 127. The free end of the clasp 122 is arranged to be secured to the relatively stationary element by means of another lug 129 also secured to the underside of plate 119 as by welding. As will be seen in Fig. 6, this arrangement of clasp 122 provides an opening 129a through which the curved portion 112a of member 112 passes.

In order to lock the clasp 122 in the closed position I have provided the clasp 122 with ears 130 and a pin 131 extending through suitable openings in the lug 129 and the ears 130. The pin 131 is secured in place by means of a locking member such as a ball 132 of suitable material such as steel which is held in the locking position in a suitable recess such as a circumferential groove 133 in the pin 131 by a spring 134, the bias of the spring 134 being dependent upon the position of cap 135 which is threadingly retained in a suitably threaded opening in the lug 129. The pin 131 is anchored by means of a chain 136.

As will be seen from Figs. 2 and 3, in order to retract the coupler 34 into the position shown in Fig. 3, it is necessary to disengage the lock lifter from member 112. This may be easily accomplished by hand by withdrawing the pin 131 following which the clasp 122 may be rotated about the pin 125 until the portion 112a of member 112 is released.

As best seen in Fig. 5, the plate 105a is provided with a slot 138 to permit passage of the lower ends of member 112 therethrough. In order to pivotally mount the second member or lever 113 on the locomotive frame, I have provided a bracket 139 suitably secured to the frame and a bearing block 140 secured to the bracket 139 as by welding. As shown in Fig. 5, the member 113 has two portions substantially at right angles to each other. One of these portions is provided at its lower end with a bifurcated arm 141, the lower end of member 112 being pivotally connected to the bifurcated arm 141 by means of a pin 142.

As shown in Fig. 5, the lock lifting mechanism may be provided with two members or levers 113 as well as two levers or members 114 so that the lock lifter may be operated from either side

of the vehicle. It will be observed in Fig. 5 that the horizontal portions 113a of members 113 are joined by means of a sleeve 143 and pins 144.

In order to provide a pivotal connection between member 114 and member 113, there is provided at the end of member 114 a loop 146 surrounding the portion 113a and a portion 147 extending beneath the downwardly extending portion 113b of member 113 and encircling the horizontal portion of lever 113. The upper end of member 114 is retained in position by means of a bracket 145 suitably secured to the locomotive frame.

In order to operate the lock lifting mechanism the operating handle 115 is moved toward the front of the unit. This causes the member 114 to rotate in a clockwise direction as viewed in Fig. 3 until the portion 147 engages the portion 113b. Further movement of the handle 115 and therefore member 114 will cause the member 113 to rotate in a clockwise direction about its pivot point in the bearing block 140 thereby moving member 112 in an upward direction. The upward movement of member 112 causes the lock lifter 111 to pivot in a clockwise direction about fulcrum 116 and therefore lifts the lock lifting member 117 to release the knuckle lock. Inasmuch as the details of the knuckle lock do not form a part of this invention it is not believed necessary to illustrate them.

When handle 115 is released, the parts will assume the positions shown in Fig. 2 because of their own weight. It will be seen from Fig. 3 that when the coupler 34 is in its retracted position and the closure plate 103 is in place, the lock lifting and operating mechanism is concealed, the member 112 being permitted to rest against the inner side of plate 103. When it is desired to use the coupler at the front end of one of the units 10, the closure plate 103 is removed, the coupler 34 racked out as previously described, and the clasp 122 passed around the portion 112a of the member 112 and locked to the ear 129 by inserting pin 131 in place.

A portion of the member 112a, as shown in Fig. 5, is curved radially and extended long enough to allow the coupler 34 to swing laterally of the uncoupling mechanism when the vehicle is traversing curves in the track. Thus, the lock lifter 111 and member 112 are not only pivotally and removably but also slidably arranged with respect to each other.

While I have shown a particular embodiment of my invention I do not desire my invention to be limited to the particular construction shown and described and I intend in the appended claims to cover all modifications within the spirit and scope of my invention.

What I claim as new and desire to secure by Letters Patent of the United States is:

1. In a railway vehicle, a retractable coupler, and a knuckle lock operating mechanism including a lock lifter, a first member pivotally connected to said lock lifter, a second member pivotally connected to said first member, means for pivotally mounting said second member on the railway vehicle, and means including a third member having a portion intermediate the ends thereof constructed and arranged for engagement with said second member intermediate the ends thereof and arranged to actuate said second member about its mounting upon pivotal movement of said third member into engagement with said second member for lifting said lock lifter by said first member, said first mem-

ber also being removably connected to said lock lifter for permitting disengagement therebetween during retraction of said coupler.

2. In an uncoupling device for a railway vehicle, a retractable coupler, and a knuckle lock operating mechanism for said coupler including a lock lifter, a first member removably and pivotally connected to said lock lifter, a second member pivotally connected to said first member, means for pivotally mounting said second member on the railway vehicle, and means including a third member having a portion intermediate the ends thereof constructed and arranged for engagement with said second member intermediate the ends thereof and arranged to actuate said second member about its mounting upon pivotal movement of said third member into engagement with said second member for lifting said lock lifter by said first member, said lock lifter being arranged for disengagement from said first member in the retracted position of said coupler.

3. In an uncoupling device for a railway vehicle, a retractable coupler, and a knuckle lock operating mechanism for said coupler including a lock lifter, a first lever pivotally connected to the lock lifter, said lock lifter being slidably associated with said first lever, a portion of said first lever being curved to allow relative lateral movement between said lifter and said first lever as said coupler swings during traversal of a curve by said vehicle, a second lever pivotally connected to said first lever, means for pivotally mounting said second lever on the railway vehicle, and means including a third lever having a portion intermediate the ends thereof constructed and arranged for engagement with said second lever intermediate the ends thereof and arranged to actuate said second lever about its mounting upon pivotal movement of said third lever into engagement with said second lever for lifting said lock lifter by said first lever, said first lever also being removably connected to said lock lifter for permitting disengagement therebetween during retraction of said coupler.

4. In an uncoupling device for a railway vehicle, a retractable coupler, and a knuckle lock operating mechanism for said coupler including a lock lifter, a first substantially U-shaped lever pivotally connected to the lock lifter, said lock lifter being slidably associated with said first lever, a portion of said first lever being curved

5 to allow said lifter to slide there-along as said coupler swings during traversal of a curve by said vehicle, a second lever pivotally connected to said first lever, means for pivotally mounting said second lever on the railway vehicle, and means including a third lever having a portion intermediate the ends thereof constructed and arranged for engagement with said second lever intermediate the ends thereof and arranged to actuate said second lever about its pivotal mounting upon movement of said third lever into engagement with said second lever for lifting said lock lifter by said first lever, said first lever also being removably connected to said lock lifter for permitting disengagement therebetween during retraction of said coupler.

5. In a railway coupler device of the type including a coupler housing having an opening, a coupler arranged and constructed for reciprocation outwardly into a coupling position and for retraction inwardly into said housing whereby a cover plate may be placed over said opening when said coupler is in retracted position in order to present a smooth continuous surface, the combination of a lock lifter, a coupler operating device arranged to be operated by said lifter, said lock lifter being provided with a releasable clasp and a relatively stationary element supported from said operating device, a member arranged for engagement by said clasp, and means associated with said member for causing operation of said lock lifter, said clasp being pivotally supported from said element, said clasp and said element having aligned openings in the closed position of the clasp, means for locking the clasp to said element including a pin arranged to be passed through said openings, said pin being provided with a recess, a locking member arranged for locking engagement in said recess, and means biasing said locking member to its recess engaging position, the aforementioned parts being so constructed and arranged that the clasp may be selectively operated manually to release the first-mentioned member in order to permit retraction of the coupler into the housing thereby permitting the cover to be placed over said opening or to engage the first-mentioned member in the extended position of the coupler thereby permitting operation of the lock lifter by said means.

OLE K. KJOLSETH.

CERTIFICATE OF CORRECTION.

Patent No. 2,239,427.

April 22, 1941.

OLE K. KJOLSETH.

It is hereby certified that error appears in the printed specification of the above numbered patent requiring correction as follows: Page 3, first column, line 47, for the word "suitably" read --suitable--; same page, second column, line 72, claim 1, for "mounting upon pivotal" read --pivotal mounting upon--; page 4, first column, lines 15 and 16, and line 40, claims 2 and 3 respectively, for the words "mounting upon pivotal" read --pivotal mounting upon--; and that the said Letters Patent should be read with this correction therein that the same may conform to the record of the case in the Patent Office.

Signed and sealed this 3rd day of June, A. D. 1941.
